UNITED STATES PATENT OFFICE.

MALCOLM L. ORD, OF ST. LOUIS, MISSOURI.

ELECTRICAL AUTOMATIC REPEATING MECHANISM FOR AUTOMATIC PHONOGRAFS.

Application filed July 14, 1921. Serial No. 484,715.

To all whom it may concern:

Be it known that I, MALCOLM L. ORD, a citizen of the United States, residing at St. Louis, in the county of St. Louis and State of Missouri, have invented a new and useful Electrical Automatic Repeating Mechanism for Automatic Phonographs, of which the following is a specification.

The object of my invention is to provide novel electrical means for automatically closing an electric circuit whereby to throw into operative engagement a suitable mechanical device adapted to stop the reproducer and move same to position for repeating a record or beginning a new record, adapted for use with any and all types of disc phonograph records, irrespective of the diameter, size, thickness or length of tone grooves in such records, and especially to provide a mechanism adapted for use as an improvement on the automatic phonograph disclosed in my pending application Serial #401,105, filed August 4th, 1920.

I attain these and other objects of my invention by the mechanism disclosed in the accompanying drawing in which—

Fig. 1 is a top plan view of my invention;

Fig. 2 is a horizontal longitudinal section of same, partly in elevation, the section line being taken substantially on the line 2—2 of Fig. 3, but with a portion of the smaller end of the telescopic tube 14 broken away, and a part of members 18 and 19 also shown in section;

Fig. 3 is a vertical longitudinal section on line 3—3 of Fig. 1;

Fig. 4 is an end elevation of the mechanism;

Fig. 5 is a transverse section on line 5—5 of Fig. 2; and

Fig. 6 is a complete diagrammatic view of the circuits employed in the repeating mechanism and the rest of the automatic phonograph as well.

Like characters of reference designate like parts in each of the several views.

Referring to the accompanying drawings illustrating my invention, I provide a suitable movable casting 7 on which is cast the first section of the telescopic tone arm 14. Mounted on bosses 37 of casting 7 are tracks

5 and 5' which are insulated by suitable insulation bushings 6 as shown in Fig. 1. At the other end of the tracks insulated bar 11 connects the tracks 5 and 5' making each one a path for either a positive or a negative current. From the bars or tracks 5 and 5' the current is taken to the carriage 10 by means of rollers 25, and is then conducted to the side bars 24 of the carriage 10. I provide a suitable housing 17 supporting the lead screw 16 which moves the carriage 10 along the record while playing at the proper thread pitch of the record by means of a correspondingly threaded nut 15 when the tone arm is lowered to playing position. The top of the carriage is rubber thus insulating the circuits from one another.

I provide a reproducer 1 attached to the arm 1' and pivotally mounted to the carriage support bracket 18 as shown in Fig. 1, by means of an insulation bracket 19 through the pivoted arms 1' and 1'' as shown in Fig. 2. When in playing position on the record reproducer 1 is held in central location under carriage 10 by means of feather coil springs 4 and 4', and midway between the platinum points 3 and 3'. The platinum points 3 and 3' are contact points for an electric circuit from bar or track member 5 by means of the busbar 9 which is connected to carriage bracket 18 by means of wire 21 as shown in Fig. 1. Busbar 9 is insulated from track 5' by suitable insulation 35 as shown in Fig. 2.

Reproducer arm 1' carries platinum points 2 and 2' which are positioned directly opposite the corresponding platinum contact points 3 and 3' respectively as shown in Fig. 1. These contact points complete a circuit through reproducer arm 1' mounted on insulated bracket 19 by means of wire 20 which is connected to side bar 24 of the carriage. Wires 22 and 23 which lead to tracks 5 and 5' with which they contact at points 8 and 8', connect with a suitable coil switch to cause the mechanical operation of any desired mechanism for record changing or repeating, the device being specially designed for operation with the mechanism disclosed in my application Serial #401,105, whenever contact points 2' and 3' or contact points 2 and 3 come into contact with each

other and thus close the circuit. Inasmuch as the reproducer remains in its central position under the carriage at the start of the record, due to the action of coil springs 4 and 4' and continues thus to remain throughout the playing of the record, these contact points 2' and 3' and 2 and 3 respectively are held separate from one another. This is because lead screw 16 being operated with 10 the record causes the carriage to follow the reproducer synchronously and keep the contact points separated. However, at the end of the record the needle reaches the last groove and remains there in the case of 15 some records due to lack of further advance because of a lack of further groove on the record. But the lead screw 16 continues to force carriage 10 along by means of its operative contact with the threaded nut 15. 20 This operation causes the coil spring 4 to compress. Reproducer 1 carrying contact point 2 while remaining practically stationary in reality has a slight oscillating motion at the portion where it is pivotally 25 mounted at 19. As the carriage advances and compresses spring 4' it brings contact points 2 and 3 into contact, closing the circuit and magnetizing the coil switch which 30 operates the mechanism to shift the reproducer to its initial position.

In other classes of records where no last annular groove is provided the needle runs out on the steeper-pitched inwardly extending spiral groove in which the tone groove 35 terminates on that part of the record not provided with tone grooves, compressing spring 4' and causing contact points 2' and 3' to come into contact and cause a similar closing of the circuit and resetting of the 40 reproducer to initial playing position.

Inasmuch as the records on the market are not standardized I have devised means to take care of the class of records which has a fast lead or spiral groove leading from 45 the last tone groove to a common inner groove at a given center and to do this I have provided contact point screw 28, as shown in Fig. 1 threaded into insulated bar 11 and adjustable by means of lock nut 31. 50 This contact screw gets its circuit from bar or track 5 by means of busbar 32.

In operation, when the needle hits the fast lead or spiral groove that leads from the end of the tone groove to an inner groove 55 on the record, it carries the reproducer 1 forward to meet contact 28, thus completing circuit through platinum plate 29. This contact is merely an auxiliary or safety device to cause a quick action should contact 60 points 2' and 3' fail to come into engagement. Contact points 3' and 3 are mounted on springs to allow slight additional travel of reproducer after the points have come in contact. This allows leeway so that the

needle will not be forced across the record 65 and scratch it by the lead screw forcing the carriage against it before the resetting mechanism is actuated.

The closing of any of these contact points causes the mechanical action which raises 70 the tone arm and returns the reproducer to starting point, which action by means of springs 4 and 4' automatically starts reproducer and lead screw off at the same speed, the circuit having thus been broken 75 between contact points 3' and 2', contact points 2 and 3, or contact points 28 and 29, as the case may be.

In the class of records such as Edison's, 80 which are very thick and which have qualities not pertaining to the other class of records, namely too shallow a tone groove to be absolutely safe to depend on the points already described, I have provided an additional set of contact points 30' on the reproducer 1 and a busbar 27 hingedly mounted on pivot 34 on side bar 24 of carriage and through which it receives its current. Referring to Fig. 2, I have provided weight 36 at the free end of the busbar, and have 90 also provided stop bracket 33 to limit its downward motion.

Busbar 27 is limited to vertical motion, 95 having no horizontal motion. In the center and directly over insulated shoe 30, mounted on reproducer 1, I have provided contact point 27'. At the beginning of an Edison record, which is much thicker than other records, the reproducer is lowered as in the previous case, but on account of the thickness of the record it is raised considerably higher, bringing insulating shoe 30 under point 27' and in contact therewith, raising busbar 27 and bringing weight 36 into action as stop 33 is then inoperative. As in 100 the previous cases, the lead screw follows the reproducer and until the end of the record is reached, point 27' rests on insulated shoe 30, but at the end of the record the reproducer either immediately starts toward 105 the center of the record in the steeper-pitched inwardly extended spiral groove where one is provided at the end of the tone grooves, or remains in the last annular groove, there being no standardized construction adopted by the manufacturers. In either instance, a forward or backward movement of the reproducer causes contact point 27' of the weighted busbar 27 to come 110 in contact with contact points 30' (see Fig. 120 3), to close the circuit and reset the reproducer to the beginning of the record. If the needle enters the circular groove at the end of a record the sound box will be 115 stationary while the carriage continues movement. Under those conditions 27' will engage left hand 30'. If the needle enters a steeper pitched inwardly extending spiral

groove at the end of the tone grooves of the record, the steeper pitch will cause the sound box to move more rapidly inward than the carriage and cause 27' to engage right hand 5 30'. Insulated shoe 30 is wide enough to permit of a slight variation in concentricity of record groove without allowing contact point 27' to fall in contact with contact points 30', and weight 36 by means of hinge 10 or pivot 34 allows of slight up and down movement, which also is prominent in the average phonograph record, and this range of movement also overcomes any variations due to the turntable running out of true.

15 It might be noted that when playing an Edison record contact points 2' and 3' and contact points 2 and 3 are not utilized as they are raised out of operative position; also, that Edison records do not have their 20 tone grooves approach as nearly to the center as other records and that contact points 28 and 29 do not come into action.

25 During the playing of records of types other than the Edison, contact points 30' and 27' are not in operation.

The positioning of contact points 30' relative to contact member 27 is illustrated in Fig. 3, which figure also illustrates how contact points 28 and 29 would come in contact to complete the circuit. The reason for the non-reliance on completion of the circuit to operate the resetting mechanism contact points 2 and 2' and contact points 3 and 3' together with springs 4 and 4' at the end of 35 the playing of an Edison record is that the tone groove in the record is so shallow that they will not overcome the pressure of springs 4 and 4' or cause sufficient pressure on contact points 2 and 2' or 3 and 3' or 40 points 28 and 29 to effect the closing of the circuit at any of these contact points. By utilizing contact point 27' and contact points 30' practically no pressure is needed to move the reproducer insulated shoe 30 45 under point 27', it being merely a sliding action and the weight 36 creates sufficient pressure upon contact points 27' and 30' to take the place of the tension allowable in using a laterally cut record the tone groove 50 of which is deep enough to exert the required pressure needed to throw the contact points into contact with each other.

Inasmuch as these points (28 and 29) are not required to operate until near the end of 55 the record I have provided on track 5' the insulation 5" which covers a section of 5' from the bushing 6 to a point calculated to bring rollers 25 into contact with the track only after the major part of the shortest 60 records made has been played. The object of this insulation is to insure against any possibility of these points coming into contact before the major portion of the record has been played. As long as rollers 25 are 65 on insulating material 5" no electric circuit

can be completed, but as soon as rollers 25 pass over insulation 5" onto the circuit carrying track 5', a completion of the circuit through the contact points mentioned is possible.

70 Referring to Fig. 6 of the drawing there is illustrated the full electric circuit of which the mechanism disclosed in Figs. 1 and 2 forms a part. The closing of the switch 199 starts the rotation of the turntable which has been elevated into playing position. The closing of switch 200 introduces the main current into transformer 201. The current leaves transformer 201 at 6 75 volts through busbars A and B which supply current to the various coils operating the machine from this transformer current. When the playing of the record has been completed one of the various sets of contact points previously described in this specification is closed and the circuit completed, the circuit including switch magnet 59 to which it is led from main busbar B, at C, and leaving magnet 59 at D, following wire 22 to binding post 8 placed on end 80 track 5. This grounds the circuit to all metal parts except the tone arm assembly, allowing it to follow to the contact points above described and illustrated in Figs. 1 and 2, to wire 23, completing circuit at G 85 with main busbar A.

90 The closing of the above described circuit energizes switch magnet 59 which attracts L-shaped magnet 60, causing hook 64 to release movable circuit contact lever 62 which falls in contact with stationary circuit contact 63. This action closes the circuit, energizing solenoid 56. This circuit starts at H where current is tapped from main busbar B, entering solenoid 56 at I and leaving 95 same at J, where it is led to movable circuit contact lever 62 by wire K through stationary contact 63, completing circuit to wire L which joins busbar A at M. The energizing of solenoid 56 causes steel core 53 100 to recede within the solenoid in turn actuating mechanism which raises the tone arm, brings a new turntable into playing position and returns the reproducer by gravity 105 to the starting point of the record just 110 brought into position for playing, as illustrated in Fig. 7.

Magnetic switches 58 and 170 act primarily as impulse switches to throw into operation the permanent switches at movable circuit arm levers 62 and 174. This is necessary because the closing of the contact points on the mechanism illustrated in Figs. 1 and 2 is only momentary.

115 When it is desired to repeat a record any 120 one of the movable toothed slides 180, as shown in Fig. 6, corresponding to the particular record to be repeated is drawn out of the slide table 177 the number of notches 125 corresponding to the number of times it is 130

desired that that particular record be repeated. These sliding tooth bars 180 are set manually before the machine is started, to control the number of times any desired 5 record is to be repeated. As bar 178 advances any of these slides 180 projecting out one or more teeth enter between springs of electrical spring switch 194, in the order in which the records are to be repeated and 10 close the circuit, and in connection with the circuit closing mechanism illustrated in Figs. 1 to 6 inclusive and above described cooperate to cause the repetition of the record for the predetermined number of 15 times.

What I claim is:

1. In an electrically operated phonograph, the combination of a reproducer, means for mounting said reproducer, said 20 means permitting of a limited degree of both lateral and vertical movement, and a plurality of electrical contact points arranged to permit of one or more of said contacts being closed when either lateral 25 or vertical movement of the reproducer occurs, for the purpose of electrically actuating mechanism to reset the reproducer.

2. In an electric phonograph of the class described having means for automatically 30 resetting the reproducer to starting position on a record when it reaches the end of the tone groove of the record, the combination of spaced track members, a carriage rollably mounted on said track members, 35 a reproducer pivotally mounted on and carried by the carriage, a lead screw positioned in proximity to and parallel with the track members, said lead screw having threads corresponding in pitch with the 40 tone groove of the record, a threaded nut attached to the carriage and engaging the lead screw whereby when the reproducer is moved out of its normal position on reaching the end of the open groove it will close 45 an electrical circuit to actuate mechanism to reset the reproducer to starting position.

3. In combination with the apparatus described in claim 1, featherweight springs engaging the free end of the reproducer to 50 normally hold same spaced from the contacts which close the circuit when the reproducer is moved in a lateral direction, as occurs when it reaches the end of the open groove.

4. In combination with the apparatus described in claim 2, a hingedly mounted weight bar positioned above the reproducer, said bar having contact points, the reproducer also having a correspondingly positioned contact adapted to engage the previously mentioned contacts to close the circuit, whereby to actuate mechanism for resetting the reproducer to starting position.

5. In an electrical automatic phonograph, 65 having means for resetting the reproducer

when it reaches the end of the tone groove of a record, the combination of telescopic arm, spaced parallel tracks, a carriage rollably mounted on said tracks, spring means for preventing lateral movement of the reproducer to close the circuit until it reaches the end of the groove, a plurality of contact points arranged to positively close the circuit when the end of the tone groove is reached, a busbar positioned transversely 70 of the tracks and included in the electric circuit, one of the tracks having insulation extending a sufficient portion of the track to positively prevent the closing of a circuit until the reproducer needle has passed 75 over the major portion of the record, and means for actuating the carriage and reproducer carried thereby in synchronism with the rotation of the record.

6. In an electric automatic phonograph 80 having electric control means for resetting the reproducer when it reaches the end of the tone groove of a record, the combination of a telescopic tone arm, a reproducer positioned at the end of said telescopic tone 85 arm, spaced parallel tracks, a carriage rollably mounted on said tracks, spring means for preventing lateral movement of the reproducer to close the circuit until it reaches the end of the tone groove, a plurality of contact points arranged to positively close 90 the circuit when the end of the tone groove is reached, a busbar positioned transversely of the tracks and included in the electric circuit, one of the tracks having insulation 95 extending a sufficient portion of the track to positively prevent the closing of a circuit until the reproducer needle has passed over the major portion of the record, means 100 for actuating the carriage and reproducer carried thereby in synchronism with the rotation of the record, said means including a lead screw having threads corresponding in number per inch to the threads on the particular record to be played, and means 105 for operatively connecting said lead screw with the carriage which carries the reproducer, substantially as and for the purposes 110 described.

7. In combination with the device described in claim 5, means for regulating the distance of one of the contact points laterally from the reproducer to permit of its adjustment of the reproducer for operation on different types of phonograph records.

8. As a new article of manufacture for use in connection with a reproducer resetting mechanism in an automatic phonograph of the class described, the combination of a reproducer mounting means for said reproducer adapted to permit both lateral and vertical movement of the reproducer, the reproducer having electrical contact points, and contact points on the mechanism carrying the reproducer, whereby an 120 125 130

electric circuit may be closed on either lateral or vertical vibration of the reproducer of a predetermined extent.

9. In an electrical phonograph, the combination of a reproducer, mounting means for said reproducer, said mounting means permitting of both lateral and vertical movement of the reproducer, contact points

on the reproducer, a rollably mounted carriage which moves with the reproducer, a weighted spring busbar supported on said carriage, depending contact members disposed to engage upstanding contact members of the reproducer upon vertical movement of same. 10

MALCOLM L. ORD.
